UNITED STATES PATENT OFFICE.

NILS M. ROSENDALH, OF CHICAGO, ILLINOIS, ASSIGNOR TO FREDERICK C. AUSTIN, OF CHICAGO, ILLINOIS.

WINDOW-VENTILATOR DUST-COLLECTING MECHANISM.

1,154,060.

Specification of Letters Patent. Patented Sept. 21, 1915.

Application filed January 30, 1911. Serial No. 605,349.

To all whom it may concern:

Be it known that I, NILS M. ROSENDALH, a citizen of the United States of America, and resident of Chicago, Cook county, Illinois, have invented a certain new and useful Improvement in Window-Ventilator Dust-Collecting Mechanism, of which the following is a specification.

My invention relates to window ventilators of the kind in which a box or hollow structure is mounted in a frame which is adapted to be placed in the window below the lower sash thereof.

It relates more particularly to that type of window ventilator in which the dust-catching mechanism that purifies the air before it passes into the room is mounted in a receptacle that slides like a drawer in and out of the said box or hollow structure.

Generally stated, the object of my invention is to provide an improved and highly efficient window ventilator of the foregoing general character.

A special object is to provide improved and highly efficient mechanism for catching the dust, which can be readily removed and cleaned, and which will tend more effectively to purify the air without appreciably or undesirably retarding the free and easy passage or influx thereof through the ventilator and into the room to be ventilated.

It is also an object to provide certain details of construction tending to increase the general efficiency of a window ventilator of this particular character.

To the foregoing and other useful ends my invention consists in matters hereinafter set forth and claimed.

In the accompanying drawings Figure 1 is a transverse section of a window ventilator embodying the principles of my invention, showing the adjacent portions of the window sill and sash in section, and illustrating the manner in which the ventilator is placed in position in a partially open window for use in ventilating the room. Fig. 2 is a perspective of one end portion of the receptacle or drawer that contains the dust-catching mechanism. Fig. 3 is a perspective of one end portion of the box or hollow body structure in which the said receptacle or drawer is inclosed and held in place.

As thus illustrated, my invention comprises a rectangular frame A which is adapt-

ed to be placed upon the window sill B, in the manner shown, so that the lower edge of the lower sash will rest upon the top of said frame. The sheet-metal box or hollow body structure D has a depressed and perforated intake or outer end wall d that inclines outwardly so that it faces downward in the manner shown. There is a lip d' at the upper edge of this perforated intake or end wall which serves as an over-hang to prevent rain or snow from clogging the perforations in the intake, the said lip serving to bring the drip a sufficient distance away from the said perforations to accomplish this purpose. The top wall of the box has a short outer portion d² that inclines downwardly at a sharper angle than the balance thereof, and the bottom wall has a still shorter portion d³ that has the same angle, so that the outer end portion of the box is in effect bent or deflected downward. The inner end of said box is provided around its mouth with flanges d⁴ by which it is securely fastened to the frame A in any suitable manner.

The receptacle or drawer E is provided with straight sides and bottom, and with an inclined outer end wall e, which latter is perforated. The said receptacle or drawer is adapted to fit and slide in the said box D, as shown in Fig. 1, and has a rounded or outwardly bulging outer end wall e' provided near its upper edge with a row of slots or openings e² that serve as the means by which the air is allowed to escape from the ventilator into the room. These openings or slots are controlled by a sort of damper comprising a curved plate e³ that fits and slides up and down on the inner surface of the wall e, and for this purpose the said damper plate is provided with a knob or handle e⁴ by which it is moved up and down to open and close the said slots or openings. The transverse partitions e⁵, e⁶ and e⁷ are inclined forward or outward and secured in place with their lower edges at or near the bottom of the receptacle or drawer, and with their upper edges provided with flanges which are disposed a distance below the top wall of the box. These partitions, like the wall e, are perforated throughout the upper half of each wall, approximately, whereby the lower half of each wall serves as a sort of baffle plate for directing the current of air upward. The three similar transverse

partitions e^8 , e^9 and e^{10} alternate with said other partitions, and are perforated throughout the lower half, approximately, of each partition. These partitions are also 5 inclined forward and outward, but unlike the first-mentioned partitions they have their upper edges secured in place, or disposed as near as possible, to the top wall of the box, and their flanged lower edges disposed a distance above the bottom of said box. The sheet of porous and flexible material e^{11} has one end thereof removably fastened at e^{12} to the inner surface of the wall e , and the other end thereof fastened at e^{13} 10 to the flanged upper edge of the wall e^5 , in the manner shown in Fig. 1. The said sheet of flexible and porous material passes from e^{12} downward and under the flanged lower edge of the wall e^{10} , then upward and over the flanged upper edge of the wall e^7 , then 15 downward and under the flanged lower edge of the wall e^9 , then upward and over the flanged upper edge of the wall e^6 , then downward and under the flanged lower edge 20 of the wall e^8 , and then upward to its other point of attachment e^{13} upon the under side of the flanged upper edge of the wall e^5 at the other end of the receptacle or drawer. The said flexible and porous material may 25 be of any suitable character, such as cheese cloth or any other suitably porous cloth, and it will be understood that it is preferably of the same width as the interior of the receptacle or drawer. With this arrangement 30 the interior of the drawer is divided by said partitions into a number of transversely disposed compartments, and by the said sheet of cloth or other material into upper and lower compartments. 35

40 In use, the mode of operation is as follows: Outside air passes through the perforated wall d and into the interior of the box at the outer end thereof. A portion of such air then passes through the perforated wall e at a point above the cloth or flexible material e^{11} , and the balance of the incoming air passes through said wall e at a point below said sheet of cloth or flexible material. The double air currents are thus forced to 45 zig zag up and down through the interior of the receptacle or drawer in the manner indicated by the arrows in Fig. 1, and with the result that dust is precipitated by the baffle plates or imperforate portions of the partitions, and caught by the porous cloth before 50 the air finally passes from the interior of the drawer through the openings e^2 and into the room. The circuitous paths thus provided for the incoming air, and the back and forth arrangement of the cloth or porous material, combine to produce a very thorough 55 purification of the air as it passes through the ventilator. Some air, of course, will pass through the cloth, and thus the latter serves also as a filter for the air. Also,

it has a rough surface which collects the dust. The dust thus collected can be easily gotten rid of, after an accumulation thereof, by pulling out the drawer and removing the cloth or other material therefrom.

When thoroughly cleaned the cloth can be replaced in the drawer, and the latter can be returned to its position in the box.

From the foregoing it will be seen that I provide a simple and improved window 75 ventilator in which readily removable means are provided for catching the dust and thereby purifying the air before it escapes into the room.

I do not limit myself to the exact construction shown and described.

What I claim as my invention is:—

1. A window ventilator dust catching mechanism comprising a zigzag strip of cloth, and means coöperating therewith, 85 serving to cause the air to follow the zigzag course of the cloth.

2. A window ventilator dust catching mechanism comprising a zigzag strip of cloth, and means coöperating therewith, 90 serving to cause the air to follow the zigzag course of the cloth, said means including a series of perforated plates.

3. A window ventilator dust catching mechanism comprising a zigzag strip of cloth, and means coöperating therewith, 95 serving to cause the air to follow the zigzag course of the cloth, said means comprising a series of plates which deflect the air and hold said cloth in position.

4. A window ventilator dust-catching mechanism arranged for causing the air to zigzag up and down in passing through the ventilator, said mechanism comprising a zigzag strip of cloth arranged for dividing the air into upper and lower currents, and upper and lower plates holding the cloth in position, said upper plates alternating with the lower plates and providing passages for successively impinging the air current 100 against the cloth.

5. A window ventilator dust-catching mechanism arranged for causing the air to zigzag up and down in passing through the ventilator, said mechanism comprising a flexible sheet of porous material arranged for dividing the air into upper and lower currents, and means providing inlets for both of said currents of air.

6. A window ventilator dust-catching mechanism arranged for causing the air to zigzag up and down in passing through the ventilator, said mechanism comprising a series of inclined plates extending transversely of the said ventilator, the alternate plates being perforated at their upper portions only, the intermediate plates being perforated at their lower portions only, and fibrous deflecting means arranged opposite each perforated plate section, said alternate 120

plates providing passages for the air above their upper edges, and said intermediate plates providing passages for the air below their lower edges.

- 5 7. A window ventilator dust-catching mechanism having means for causing the air to zigzag up and down in passing through the ventilator, and a receptacle containing said mechanism, said means including a
10 readily removable sheet of cloth which is flexed alternately up and down to provide a

series of opposing surfaces which catch the dust, and means for admitting air above and below said cloth at the outer end of said ventilator.

15

Signed by me at Chicago, Cook county, Illinois, this 24th day of January, 1911.
